UNITED STATES PATENT OFFICE.

HENRY ROLLAND ADAMS, OF WAYSIDE, TEXAS.

REPRODUCING DEVICE FOR GRAPHOPHONES.

1,301,631.

Specification of Letters Patent. Patented Apr. 22, 1919.

Application filed May 20, 1918. Serial No. 235,604.

To all whom it may concern:

Be it known that I, HENRY R. ADAMS, a citizen of the United States, residing at Wayside, in the county of Armstrong and State of Texas, have invented new and useful Improvements in Reproducing Devices for Graphophones, of which the following is a specification.

This invention relates to reproducing devices for graphophones, and one object is to provide certain novel means for mounting the diaphragm in order that the vibrations shall be transmitted from each side thereof to a plurality of ducts having connection 10 with a main duct or tone arm through which the sound passes to the horn or the like.

A further object is to provide a casing comprising a plurality of semispherical members with means for mounting a diaphragm across the chamber formed by said members, and means for connecting the opposite sides of the semispherical members with a common air duct, or tone arm.

A still further object is to provide certain novel means for mounting the needle and comprising a conical member carried within a tapered seat and separated from said seat by a sleeve of fiber, this conical member having connection with the arm connected with 25 the diaphragm of the reproducing device.

With the foregoing and other objects in view the invention consists in the novel construction, combination, and arrangement of elements hereinafter described and claimed. 30 Figure 1 is a longitudinal central section illustrative of the best practical embodiment of my invention that I have as yet devised; the said section being on the line 3—3 of Fig. 2.

Fig. 2 is a view, partly in plan and partly in section, with the upper casing section removed.

Fig. 3 is a section taken in the plane indicated by the line 3—3 of Fig. 2.

A diaphragm 10 is mounted diametrically of a spherical chamber comprising a plurality of semispherical sections, each of these sections being provided with an opening having connection with a duct through 45 which the sound vibrations pass to a common outlet; the sections of casing are designated 11, and 12, and each section has connected therewith a duct 13 having a flanged

portion 14 near one end, the extreme end of the duct entering an aperture 15 provided in 55 each side wall of the common outlet, which may be referred to as the tone arm, and is designated 16. The ducts 13 are of about the form shown, and positive connection with the common outlet 16 is maintained 60 by means of a threaded annular member 17 connecting the casing sections 11 and 12. The diaphragm is mounted between these sections, and any suitable gasket or gaskets 18 are located at this point. Casing section 11 carries an outwardly extending flange 19 internally threaded and engaged by the ring member 17 in securing the casing sections together. The casing as a whole, including ducts 13, is movable toward 70 and away from the record, in view of the connection at 20.

The diaphragm 10 has connected therewith, an arm 23 passing through a packing member 24 in the wall of a casing, and having connection with the cone member 25 provided at one end with an extension 26 constituting a needle holder. The needle is shown at 27. The cone member 25 is under slight pressure, this pressure being exerted 80 by spring 28 mounted as shown. Between the cone member and the casing 30 therefor is a fiber sleeve 31 serving to eliminate, so far as possible, those vibrations which interfere with the proper movement of the diaphragm for reproducing the record in the most satisfactory manner. The object in providing an air chamber on each side of the diaphragm is to produce a larger volume 85 of sound and a tone of finer quality. 90

What is claimed is:

In a device of the class described, a casing, a diaphragm mounted within the casing, an arm connected with the diaphragm, a needle holding device comprising a cone member, a 95 casing therefor including a stationary casing element and a detachable threaded element having a bore of varying cross section, receiving the cone member, a fibrous sleeve between the casing and cone member, a spring 100 for retaining the cone member and sleeve in positive contact, an extension carried by the cone member, and a needle mounted in said extension.

In testimony whereof I affix my signature. 105
HENRY ROLLAND ADAMS
